DISPLAY SIGN

Joseph N. Klema, Austin, Minn.

Application May 19, 1936, Serial No. 80,624

3 Claims. (Cl. 40—139)

This invention relates to display signs and is an improvement over the construction embodied in my Patent No. 2,036,147, dated March 31, 1936.

An object of this invention is to provide a sign construction including a fixed sign portion and a movable sign portion, each of which bears an incomplete part of the sign which is adapted to be completed upon movement of the movable sign portion to one position with respect to the other sign portion and wherein means is provided for momentarily interrupting the movement of the movable sign portion when the two sign portions are in a position to complete the sign.

Another object of this invention is to provide in a sign of this character an operating means for the movable portion of the sign which may be moved continuously while, at the same time, the movable portion of the sign will be interrupted in its movement when one or more sign portions are completed.

The above and various other objects and advantages of this invention will in part be described in, and in part be understood from the following detail description of the present preferred embodiment, the same being illustrated in the accompanying drawing, wherein:

Figure 1 is a front elevation of a sign constructed according to an embodiment of this invention.

Figure 2 is a fragmentary rear elevation of the sign showing the operating means for the movable portion of the sign.

Figure 3 is a sectional view partly broken away taken on the line 3—3 of Figure 1.

Figure 4 is a fragmentary rear elevation of a modified form of operating means for the movable portion of the sign.

Figure 5 is a similar view of another modification of the operating means.

Figure 6 is a fragmentary front elevation of a modified form of sign construction embodying the interrupted movement feature of the movable portion of the sign.

Figure 7 is a fragmentary sectional view taken on the line 7—7 of Figure 4.

Figure 8 is a sectional view taken on the line 8—8 of Figure 5.

Referring to the drawing wherein like symbols designate corresponding parts throughout the several views, the numeral 10 designates generally a fixed sign construction including upper and lower sign portions 11 and 12 respectively, and opposite end sign portions 13 and 14. These sign portions 11, 12, 13, and 14, in the present instance, are secured together in the form of a rectangle

and this rectangular sign portion which is open at the center is secured to a solid back frame member 15 having a base 16 at the lower edge thereof.

The upper sign member 11 has substantially one-half of a sign of suitable character disposed on the outer face thereof, as indicated at 17, and the lower sign member 12 has a sign portion 18 thereon which constitutes substantially one-half of a sign for registry with a movable sign member, as will be hereinafter described. In like manner, the vertical sign member 13 has one-half of a sign disposed thereon, as indicated at 19, and the opposite end 14 is also provided with one-half of a sign, as indicated at 20.

The lower sign member 12 is provided with a guide or track 21 extending longitudinally thereof which is disposed between the rear walls 15 and the rear side of the sign member 12. A movable sign member including a horizontally disposed sign 22 and movable panels or sign members 23 and 24 are disposed within the area formed by the fixed sign members 11, 12, 13, and 14, and are provided with a slide portion 25 which engages within the guide or track 21. The horizontal sign member 22 is provided with indicia 26 comprising one-half of the sign which is carried by the lower sign member 18 and which, at the end of one movement of the movable sign, is adapted to come into registry with the lower half of the sign, as indicated at 18, so as to complete a word or words or other suitable character. An upper horizontal sign member 27 is secured to the movable panels or end members 23 and 24 and is provided with indicia 28 adapted to register with the indicia 17 at substantially the end of one movement of the movable sign member.

The area within the movable sign member comprising the two horizontal portions 22 and 27 and the vertical portions 23 and 24 exposes the outer side of the back wall 15 which, in the present instance, is provided with a suitable sign, as indicated at 29. This sign portion 29 may be a word or words or a picture, or any other suitable indication which will be exposed at all times throughout the movement of the movable sign member.

The vertical sign member 23 is provided on the outer face thereof with indicia or indications 30, adapted to register with the indicia or indications 29, so as to complete a suitable sign and in like manner the vertical sign member 24 is provided with indicia 31 adapted to register with the indicia 19 so as to complete the sign carried by the end member 13.

The vertical wall 15 is provided with a pair of aligned horizontally disposed slots 32 through 35

which bolts or pins 33 are adapted to project. These bolts or pins 33 are secured to the movable sign member and, in the present instance, are secured to the lower sign member 22 and each pin 32 has an angular member 34 secured thereto which is disposed rearwardly of the rear wall 15. These angle members 34 are each provided with an opening 35 therethrough constituting a bearing for a sliding operating rod 36. 10 The rod 36 loosely engages through the openings 35 of the rearwardly extending leg of the angle members 34 and springs 37 are disposed about the rod 36 and engage at one end against the rearwardly extending leg of an angle member 34 and the opposite end of each spring 35 is adapted to engage against a washer or collar 38 which is fixed to the rod 36. The rod 36 is reciprocated back and forth upon rotation of a worm gear 39 rotatably carried by a bearing structure 40 which 20 is secured to the base 16.

A pitman or link 41 is secured at one end to an eccentrically disposed pin or trunnion 42 carried by the gear 39 and the opposite end of the pitman or link 41 is secured to a collar or block 25 43 which is fixed to the rod 36.

In Figure 4 there is shown a modified form of operating means for the movable sign which comprises an elongated rod 44 provided at opposite ends thereof with elongated slots 45. This 30 rod 44 is adapted to loosely engage the headed pins 33 and reciprocating movement of the rod 44 is effected by a pitman 41a which is secured to a gear 39a in the same manner as the gear 39. The rod 44 is provided with a pair of springs 46 35 disposed at the inner ends of the slots 45 and one end of each spring is secured to the rod 44 and the opposite end of each spring 46 is provided with an eye 47 engaging a pin 43. In this instance, the movement of the slide is effected by 40 pulling through the spring 46.

In Figure 5 there is disclosed another form of operating means for the movable slide and in this form an elongated bar 48 extends between the rearwardly extending pins 33 of the movable 45 slide and is fixed thereto, this rod or bar 48 being provided with openings 49 adjacent the opposite end thereof. The interrupted movement of the movable slide is effected by means of a pitman 41b which is provided with an elongated slot or opening 50 adjacent one end thereof in which is received a pin 51 fixed to the bar 48. Springs 52 are disposed within the slot 50 and engage the pin 51 so as to normally hold this pin 51 in substantially the longitudinal center 55 of the slot 50.

Figure 6 shows a modified form of sign construction and operating means therefor in which a pair of sign members 53 and 54 are provided which are moved one relative to the other by 60 means of a forked operating member 55 pivoted as at 56. The opposite ends of the forked portions 57 of this member 55 are secured as by links 58 to the upper ends of the sign members 53 and 54 so that these sign members 53 and 54 65 will move in opposite directions under the rocking of the forked member 55. An elongated rod 59 is slidably through the stem portion of the forked or Y member 55 being provided with a head 60 at one end thereof and the opposite end 70 of the rod 59 is secured to a pitman 61 which is secured to an eccentrically disposed pin 62 carried by a gear 63. A spring 64 is disposed about the rod 59 and at one end engages against the stem portion of the Y member 55 and the 75 opposite end of the spring 64 engages against a

collar 65 which is secured to the rod 59. A stop member 66 is mounted in a position to stop the rocking movement of the Y member 55 when the sign portions 67 and 68 of the sign members 53 and 54 respectively are in registry. At this time, 5 the rod 59 will continue sliding movement and the spring 64 will be compressed. The showing in Figure 6 is a diagrammatic showing of a sign and operating construction in which the interrupted movement of one or more of the sign members 10 is effected.

The worm gear 39 is rotated by means of a worm 69 carried by a shaft 70 which is connected to a motor or power member 71.

In the use and operation of this device, the 15 power member 71 will rotate the gear 39 continuously and the pitman 41 will reciprocate the rod 36 back and forth. When the movable sign reaches at one end of its travel in the guide 21 and assuming that this end of the travel is the 20 end 13 of the stationary sign, the sign portions 19 and 31 will be completed. At this time, the spring 37 shown at the right side of Figure 2 will strike the rearwardly extending leg of the angle member 34 at about the time that the eccentric pin 42 is in the position shown in Figure 2. Continued rotation of the gear 39 will move the pitman 41 forwardly or to the right and also effect additional movement of the rod 36 through the guide openings 35 of the rod supporting members 34. The right hand spring 37 will thereby be compressed and at this time the movable sign member 24 will remain stationary. Continued rotation of the gear 39 will effect reverse movement to the rod 36 so as to move the movable sign in the opposite direction and when the movable sign member 34 engages against the stationary sign member 14, the left hand spring 37, shown in Figure 2, will be compressed while, at the same time, the rod 36 continues its movement to the left. This movement of the operating means for the movable sign will be a continuous movement while, at the same time, the movable sign is interrupted in its movement at each end of the stationary sign a sufficient length 45 of time to permit the reading or display of the completed sign. While the movable sign members are shown as being moved through the medium of the worm gear 39, the movable sign members may be moved by providing a disc in 50 place of the worm gear 39 and connecting this disc to a suitable power means.

The inner sign 29 is shown as a stationary sign of suitable character but this sign may also be constructed in the form of a movable sign, as embodied in my Patent No. 2,012,468 with the movable sign 29 connected by means of a rod or the like to the slide rod 26 or the like. In Figure 6, the sign members 53 and 54 may be provided with a balancing means of suitable construction in the 60 form of weights or the like so that these members may be moved by a relatively small motor or operating means.

If desired, a second pitman or link 41 may be connected at one end to the pivot 42 and at the 65 opposite end to a figure sign similar to the figure sign embodied in my prior Patent No. 2,012,468.

I claim:—

1. A sign as set forth comprising a stationary sign member, a reciprocable sign member, means for slidably mounting said reciprocable sign member for sliding movement relative to the stationary sign member, a rotatable operating means, a slidable bar, means for slidably securing said bar to said reciprocable sign member, a 75

- connecting link connecting the operating means with the sliding bar to effect reciprocity thereof upon rotation of the operating means, yieldable means interposed between the link connection and the bar supporting means whereby the bar may have continuous movement without movement of the reciprocable member at one end of the line of travel thereof, indicia carried partly on said stationary sign member and partly on said reciprocable sign member, movement of said reciprocable sign member in one direction presenting completed indicia and movement of said reciprocable sign member in the opposite direction presenting incompletely indicia. 5
15. 2. A sign as set forth comprising a stationary sign member, a reciprocable sign member, means for slidably mounting said reciprocable sign member for sliding movement relative to the stationary sign member, a rotatable operating means, a horizontally slidable bar, means for slidably connecting said bar to said reciprocable sign member, a link connecting the operating means with the sliding bar to effect reciprocity thereof upon rotation of the operating means, 20 and a spring engaging about the bar between the link connection and the bar supporting means whereby the bar may have continuous movement without movement of the reciprocable member at one end of the line of travel thereof, indicia car- 25
- ried partly on the stationary sign member and partly on the reciprocable sign member, movement of said reciprocable sign member in one direction presenting completed indicia and movement of said reciprocable sign member in the opposite direction presenting incompletely indicia. 5
3. A sign as set forth comprising a stationary sign member, a reciprocable sign member, means for slidably mounting said reciprocable sign member for sliding movement relative to the stationary sign member, a rotatable operating means, a slidable bar having an outwardly opening slot in each end thereof, spaced apart pins carried by said reciprocable sign member projecting into the slots of said bar, a link pivotally secured to said operating means and said bar and a pair of springs secured to said bar and to said pins whereby the bar may have continuous movement without movement of the reciprocable member at one end of the line of travel thereof, indicia carried partly on said stationary sign member and partly on said reciprocable sign member, movement of said reciprocable sign member in one direction presenting completed indicia and movement of said reciprocable sign member in the opposite direction presenting incompletely indicia. 10 15 20 25

JOSEPH N. KLEMA.
